MEANS FOR GUMMING OR MOISTENING
LABELS, ENVELOPES, OR THE LIKE

Heinrich Dornseifer, Berlin, Germany

Application July 29, 1936, Serial No. 93,214
In France and Germany August 5, 1935

2 Claims. (Cl. 91—50)

This invention relates to means for applying a gum or other adhesive, or for moistening a gummed or other adhesive surface, of paper, such as address or other labels, envelopes and the like.

In apparatus of this character there is provided a suitable container for the liquid to be applied to the surface of a sheet or web, such as water for moistening an adhesive surface of 10 the sheet or web, or an adhesive, such as gum in a liquid state, the liquid being applied by a device to which the liquid is transferred from the container having a portion projecting from the container, and means are provided to cause 15 the sheet or web to be guided to and pressed against the applying device to assure applying a film of the liquid to the surface of the sheet or web.

It is the object of the invention to provide an 20 improved apparatus of this character, and particularly to provide an improved construction and arrangement means to guide and press to the applying device the sheet or web to the surface of which the moisture or adhesive is to be applied.

It is a further object of the invention to provide an improved roller or rollers for transferring the liquid from the container and for applying the liquid to the surface of the article, such 30 as a sheet or web, and cause the liquid to adhere to the surface of the roller.

Additional objects and advantages of the invention will become apparent from the following description in conjunction with the accompanying 35 drawing, which illustrates certain possible forms of embodiment of the invention.

Fig. 1 is a perspective view of one form of embodiment of the invention.

Fig. 2 is a perspective view of a second form 40 of embodiment.

Fig. 3 is a side-elevational view of the apparatus according to Fig. 1, partially in section,

Fig. 4 being a similar elevational view of the apparatus according to Fig. 2.

Fig. 5 shows a modified form of embodiment 45 of the apparatus according to the invention and having a one-piece feed and pressure bar for the moistening of gummed envelopes.

In the embodiment of the invention illustrated 50 in the drawing there is provided a container 1 in the form of a trough, which is open at the top and adapted to contain the liquid utilized, such as a moistening liquid or a liquid adhesive. The means to transfer the liquid from the container and for applying it to the surface of an article

comprises two rollers 2 and 3, the roller 2 being partially immersed in the liquid in the container and the roller 3 arranged above the liquid with a peripheral portion projecting above a cover 4 closing the top of the container. Instead of two rollers one roller may be utilized, in which case the roller is arranged with a peripheral portion engaged in the liquid in the container and a peripheral portion extending above the cover 4.

The cover 4 is either made to be wholly detachable from the container 1 (Fig. 2) or it may be secured thereto by a hinge 4a (Fig. 1). It is either constructed in such fashion that it exposes a portion of the container, which is taken up by the roller 3 (Figs. 1 and 3), or, as shown in Figs. 15 2 and 4, it is furnished with an opening 5 adapted to receive the said roller.

The rollers 2 and 3 are mounted by spindles 6 and 7 in the vertical slots 8 of two bearing plates 9 (Figs. 3 and 4). These rollers are in immediate contact with each other, so that rotation of the roller 3, owing to the friction between the rollers 2 and 3, will rotate in positive rotation of the roller 2, and the liquid will accordingly be transferred from this roller 2 by way of the roller 25 3 to the articles under treatment. Dependent on the particular construction of the container cover aforesaid the plates 9 containing the bearing slots or grooves 8 will be mounted on the side walls 1a of the container or they will be mounted in direct fashion on the cover 4 and extend from the latter into the interior of the container 1. This latter embodiment will be particularly convenient if the material employed for the container 1 is glass. The bearing plates are secured 30 to the container 1 by the cover 4 by screws or rivets or in other suitable fashion.

Laterally of the roller 3 on the cover 4 there is situated the feeding and pressing device for the articles under treatment. This device in the 40 embodiment according to Figs. 1 and 2 comprises two separate and independent bars 10, the spacing between which is designated 11. This space 11 enables the article under treatment to be drawn readily between the bars 10 with the assistance of the finger. In other words the space is provided for the passage of the finger.

The bars 10 do not bear in immediate fashion against the cover 4, and there is provided between the bars and the cover a spacing member 50 12, which generally speaking will correspond with the thickness of the article under treatment and may be increased or decreased as required by varying the thickness of the bearing plates 13. The spacing between the bars 10 and the 55

roller 3 may also be varied for the purpose of precluding excessive bending of the paper in its passage through the apparatus. For this purpose slots 14 are provided in the cover or the bars and serving for the adjustable attachment of the bars by means of screws 15 engaging in said slots.

In the embodiment of the invention shown in Fig. 5 the feeding and pressing device 10 is made in one piece, so that there is no spacing 11. Since the envelope to be moistened requires to be introduced in a direction endwise and longitudinally of the bar, the bar 10 in this case is shown in Figure 5 is mounted or secured in the manner above described only at the one end. Apart from this the feeding and pressing device corresponds with that in Figs. 1 and 2.

In order to obtain a better contact of the article with the transfer roller 3, more particularly as regards the contacting of the apex of the flap of an envelope with the roller, the bar 10 may be arranged intermediate its length and accordingly opposite the middle of the roller with a projection 20 extended forwardly from the bar 25 or plate to lightly engage the roller.

To facilitate introduction of the flap of the envelope between cover 4 and bar 10 the bar may be flanged somewhat along its front edge, f. e. in the form of the wing 16.

30 In the embodiment according to Figs. 1 and 2 the bars 10 are provided along the edge directed away from the roller 3 with raised wings 16' to facilitate the introduction of the articles under treatment between the cover 4, which acts as 35 table for the articles, and the said bars. The marginal edge portion of the cover 4 is deflected slightly upwardly, as at 17, to extend adjacent the roller 3 in order better to direct the paper or the like to the roller 3, as shown in Figures 40 3 and 4.

In Figs. 1 and 2 there is shown a label or the like 18, which is located between the bars 10 and the roller 3 and is passed between these by hand in the direction of the arrow. By withdrawing the article 18 towards the front the 45 rollers 2 and 3 are caused to rotate, and in this way the liquid from the container 1 is conveyed evenly upwards and is transferred to the article owing to the roller 3 rolling over the article.

To cause the liquid better to adhere to the rollers 2 and 3, and accordingly to ensure proper transfer of the liquid to the surface under treatment, the rollers, which are preferably composed of metal (brass or the like), are furnished with longitudinal and/or transverse grooves 19 or other recesses, in or to which the liquid will properly adhere. Or if desired the rollers may be furnished with a facing of material serving to absorb the liquid.

10 The invention may be employed not only for paper articles, such as address or other labels, envelopes or the like, but also for the corresponding treatment of other articles, composed for example of cardboard, leather, fabric or the like.

Having now particularly described and ascertained the nature of my said invention, and in what manner the same is to be performed, I declare that what I claim is:

20 1. In means for applying liquid to the surface of a sheet or web, a liquid carrying trough, means within and for transferring the liquid from the trough having a portion projecting above the trough over which the sheet or web to the surface of which the liquid is to be applied is drawn, and means to guide and cause the sheet or web to be pressed against the projecting portion of said applying means, comprising a pair of bars mounted at one end on and extending inwardly 25 from opposite sides of the trough in spaced relation to and in a plane below the top of the liquid applying means, said bars being of a length to provide a space between the inner ends thereof.

2. Means for applying liquid to the surface of a sheet or web as claimed in claim 1, wherein each bar is provided at one end with a portion extending laterally from and in the plane of the bar arranged to mount the bar on the trough to have adjustment toward and away from the 40 liquid applying means, and the following marginal edge portion of the bar is flanged laterally of a face thereof to constitute a guiding wing to facilitate engaging a sheet or web below the bar.

45 HEINRICH DORNSEIFER.
